UNITED STATES PATENT OFFICE.

FRANKLIN P. BEISEL, OF POTTSTOWN, ASSIGNOR OF ONE-HALF TO JOHN H. EGOLF, OF DOUGLASSVILLE, PENNSYLVANIA.

NUT-LOCK.

SPECIFICATION forming part of Letters Patent No. 337,653, dated March 9, 1886.

Application filed December 7, 1885. Serial No. 185,011. (No model.)

To all whom it may concern:

Be it known that I, FRANKLIN P. BEISEL, a citizen of the United States, a resident of the town of Pottstown, county of Montgomery, 5 State of Pennsylvania, have invented a new and useful Improvement in Lock-Nuts, of which the following is a specification.

This improvement is more particularly related to the class of lock-nuts intended for use 10 upon the fish or splicing plates of railroad rail-joints, although adapted for general use as a lock-nut.

The object of the invention is to secure a positive lock for the nut, with any desired tension upon the bolt, so that the fish-plates may 15 be drawn together with sufficient force to sustain the rail, yet will provide for a certain amount of sliding play of the rail upon the same, thus permitting expansion and contraction to take place without disturbing the alignment of the rails. It is well known that 20 a certain amount of sliding play is desirable at the joint; but in all the lock-nuts with which I am acquainted the nut cannot be adjusted with sufficient positiveness to retain 25 the rails in sliding contact, they invariably becoming loose in a short time after adjustment. This desired result I attain by my improved mode of locking the nut, as will be 30 more clearly explained when referring to the drawings herewith, forming a part of this specification, in which like letters of reference indicate like parts.

Figure 1 represents an ordinary fish joint 35 or splice with my improved nut-locking device thereon; Fig. 2, a cross-sectional elevation on the line of one of the splice-bolts; Fig. 3, a detached elevation of the combined lock-shell and washer, the protector-case 40 shown in section; Fig. 4, a detached elevation of the washer, showing one of the recessed ways with its keeper-hook. Fig. 5 represents an exterior end view of the locking-shell with a portion of the nut-locking end 45 removed to show the locking-lugs at the inner end of the shell and upon the interior face thereof. Fig. 6 is a vertical section of the locking-shell, showing the locking-lug and nut-locking aperture.

50 In the drawings, A represents the railroad-

rail; B, the fish or splice plates; C, the usual bolts, having an enlarged body at C', to prevent turning, a head, C², and hexagon or square nut C³. The nut-locking device is composed of a washer, D, formed with a collar, D', an offset, D², and bolt-aperture D³. An annular shell, E, passes freely over the body D of the washer, and the outer end is partially closed by a ring, E', having an aperture, E², cut therein for either a square or hexagon nut, adapted to the bolt, and said aperture is cut slightly larger than the plan of said nut, so as to move freely over the same. A spiral spring, F, of suitable strength, preferably of brass wire, is adapted to slip over 60 the body D of the washer, and on screwing up the nut C³ the spring F will be compressed between the end of the annular shell E and the collar D'. Diametrically opposite, upon the body D, and reverse to each other, recesses or passages D⁴ are cut down to the level of the offset D², and of the form shown, or its equivalent, producing a keeper-hook, D⁵, upon the body of the same. Lugs E³ E² are placed diametrically opposite each other upon 65 the inner face of the shell E at its inner end. Said lugs E³ are designed to project within the shell far enough to just clear the offset D² of the washer D, and are made of a suitable size to pass freely into and around the passages D⁴ 70 and finally lock beneath the keeper-hook D⁵. A case, G, is stamped out of tin or light sheet-iron, open at the front, and with an aperture, G', in the rear to pass over the bolt C. The washer D drops freely within the case, which 75 serves to protect the combined parts from injury, and prevents tampering therewith by unauthorized persons.

To use the device, the fish-plates B and bolts C are placed upon the rail A. The washer D 80 has the spring F slipped upon the same, and resting upon the collar D'. The shell E is then placed with its lugs E³ over the offset D² and within the passages D⁴. The spring F is then compressed until the lugs E³ are 85 brought in line with the horizontal passage, when the shell is partially turned toward the right, so as to throw the lugs within the same. This done, the spring is retained in a compressed condition, and washer and shell, vir- 90 95 100

tually forming one integral piece, are placed within the case G and slipped upon the bolt C. The nut C³ is now run down upon the bolt until it contacts with the end of the washer and drawn up tightly. A smart rap of the hammer is given to the head C² of the bolt to insure snug work, and the shell E is again turned forward until the aperture E² coincides with the nut on plan, and the lugs E³ will have arrived in line with the inner vertical passage, when the resilience of the spring F will drive the shell E outward and the aperture E², surrounding the sides of the nut C³, will lock the same therein. A slight relaxation of the bolt tension is now given by a reverse turn to the nut, which at the same time lodges the lugs E³ under the keeper-hooks D⁵, and there can be no further loosening of the nut without the shell-lugs were sheared off, which is not at all likely to occur, unless intentionally done for a malicious purpose. To release the nut it is again turned to tighten up the same, which brings the lugs out from under the keeper-hooks and in line with the inner vertical passage. The shell is then shoved inward, again compressing the spring F, and being turned to the left the lugs are caught as before in the horizontal passage, and the shell is held out of the way of the nut until the same is removed, or until it is desired to replace the same.

It will be apparent that the locking device may be used without the spring, as if the shell is placed upon the washer, as described, and at the proper time, just before relaxing the tension of the nut upon the bolt, it is pulled toward the operator and made to coincide with the nut, as before. Then on relieving the strain upon the bolt the lugs will be thrown under the keeper-hooks, and no further release of the nut can take place. I prefer, however, to make use of the spring, as the outward movement of the shell toward the nut is at the proper time automatic, and the parts being held in close contact thereby there is no noise created by loose parts as there would be without the use of the spring.

The washer D and shell E and the case G, if so desired, may all be constructed of cast-iron, being adapted to be easily molded and cast of the same, and little subsequent work upon them will be requisite, after the pieces leave the tumbling-churn, to fit them for immediate application.

I am aware of much that has been done in the line of lock-nuts for railway-splices, and believe that I have developed a new and novel lock, simple in its construction, positive in its

action, and which may be repeatedly placed and removed without injury to the same.

As shown upon the splice, a portion of the washer-collar is flattened to lie upon the foot of the fish-plate or on the foot of the rail when the usual plain flat splice-plate is used. This prevents the turning of the locking device while the nut is being tightened up or released; but the nut-locking device is applicable to many other purposes, and various modes may be adopted to prevent turning—such as pins cast upon the outer face of the washer and countersunk recesses punched or formed in the contacting-surface upon which the washer is laid; or a foot may be cast upon the collar D', projecting far enough away from the same to strike a pin or resisting-abutment. To these several modes I make no claim, as the use of the device would suggest the same.

The relaxation of the bolt-tension, as described, will allow for the creeping movement due to the expansion and contraction of the rails, yet will not be sufficient to produce injurious looseness of the several parts.

Having shown the construction, use, and advantages of my improved nut-locking device, I desire to secure by Letters Patent the following claims upon the same:

1. As an improved nut-locking device, an annular shell, E, having lugs E³ at its inner interior surface and in its outer end an aperture, E², conforming with and adapted to receive the nut C³ of the bolt C, in combination with a body-washer, D, with collar D', recesses D⁴, and keeper-hooks D⁵, adapted by perforation D³ to slip over said bolt, and a spring, F, all arranged and adapted to be operated together substantially as shown, described, and for the purpose specified. 85

2. In combination with a nut-locking device consisting of a perforated body-washer, D, with passages D⁴ and keeper-hooks D⁵, formed upon or within the same, and an annular shell, E, having a nut-aperture, E², and lugs E³, adapted to move within the passages D⁴ and lock beneath the keepers D⁵, as described, an outer open case, its inner end perforated for the bolt C, said case adapted to receive the collar D' of the washer D, and to conceal and protect the spring F and contacting parts of washer and shell in the manner as shown, and for the purpose set forth. 100

FRANKLIN P. BEISEL.
